UNITED STATES PATENT OFFICE.

FRANCIS JERDONE, JR., OF CHICAGO, ILLINOIS.

CAR-BOLSTER.

No. 835,436.

Specification of Letters Patent.

Patented Nov. 6, 1906.

Application filed July 25, 1906. Serial No. 327,755.

To all whom it may concern:

Be it known that I, FRANCIS JERDONE, Jr., a citizen of the United States, residing at Chicago, in the county of Cook and State of Illinois, have invented certain new and useful Improvements in Car-Bolsters; and I do hereby declare the following to be a full, clear, and exact description of the invention, such as will enable others skilled in the art to 10 which it appertains to make and use the same.

This invention relates to bolsters for car structures, and has for an object to provide a bolster of improved form and added strength 15 embodying economy of construction.

A further object of the invention is to provide in a car-bolster improved means for connection with a single center sill of the car structure.

20 A further object of the invention is to provide in a car-bolster improved means for connecting and attaching the usual and customary truss-rods when desirable.

With these and other objects in view the 25 invention comprises certain other novel constructions, combinations, and arrangements of parts, as will be hereinafter fully described and claimed.

In the drawings, Figure 1 is a view of the 30 improved bolster in side elevation. Fig. 2 is a top plan view of the improved bolster. Fig. 3 is an end view of the bolster seen on arrow 3 of Figs. 1 and 2. Fig. 4 is a transverse sectional view of the bolster, taken on line 4 4 of Fig. 1. Fig. 5 is a detail fragmentary view of the central portion of the bolster structure, showing the center beam in section and the preferred manner of connecting the bolster and beam.

35 In its preferred embodiment the improved bolster forming the subject-matter of this application comprises a bolster-body substantially elliptical in general outline and comprising a web 10, surrounded by a flange 11, the said flange standing out and disposed substantially at right angles to the web and upon opposite sides thereof, as shown particularly in Figs. 2 and 4. The bolster-body may be formed in any approved manner, as 40 by stamping, but is preferably a steel casting formed integral throughout and also preferably formed with a plurality of openings, as 45 12, in the web 10.

At its center the web portion 10 is formed 50 with an opening 13, shaped to embrace and

fit the center beam of the car structure, (here shown as the I-beam 14,) and with thickened portions or bosses 15 and 16 surrounding the opening 13 for the purpose of strengthening the web adjacent the opening. The webs 15 and 16 are provided with a plurality of rivet-openings, as 17, and the bolster is rigidly secured to the I-beam 14 by means of angle-irons 18 and 19, disposed within four angles formed by the web of the bolster and the 60 I-beam and secured by rivets 20. To further reinforce the opening for the I-beam 14, the swivel-plate 21 is riveted rigidly to the under side of the flange 11 and extends longitudinally of the bolster across the opening 70 and is secured in any approved manner, as by rivets 22. The under flange of the bolster is also provided with downwardly-offset portions 23 to accommodate the usual antifriction-rolls to permit the bolster to oscillate 75 upon the truck. At the opposite ends the bolster is provided with an outer or end plate 23, spaced from an inner plate 24 to define an opening 25, into which the eye of a truss-rod 26 may be inserted and secured by 80 means of a bolt 27 through either one of the openings 28. The openings 28 are formed upon each side of the web 10, so that the bolster may be disposed upon the center beam interchangeably, although but one of the 85 said openings is usually employed. The openings 28 are provided with encircling bosses 29 for the purpose of strengthening the said openings and providing a bearing-surface for the head of the bolt 27 and its 90 associated nut.

At its opposite ends the bolster is provided with a normally horizontal plate-like portion 30, adapted to support beams 31, which form the side sills of the car and are provided with 95 rivet-openings 32 to receive rivets, as 33, by which the angle-iron side sills 31 are secured rigidly to the bolster.

For association with the form of bolster here shown a metal floor is preferably used 100 and supported upon transverse beams 34, which, however, forms the subject-matter of a copending application, bearing Serial No. 327,753, filed July 25, 1906, and is not herein claimed. The web 10 of the bolster may be 105 further provided with openings 35, through which may be inserted the usual train-pipes for the air-brake system and may of course be provided with such other openings as the particular system installed may render de- 110

sirable, being preferably encircled by bosses 36, so that the openings so formed do not weaken the web structure.

The connection between the bolster proper 5 and the side sills 31 is further strengthened and rigidity added by means of a tie or gusset plate 37, rigidly secured to the upper flange 11 of the bolster and bent to accommodate the lower flange of the angle-iron 31 and extending upward along the vertical flange and reveted thereto, as shown particularly in Fig. 1.

While the bolster here described is shown in association with an I-beam as the single 15 center beam of the car, it will be obvious that a single center beam of any other form may be substituted for the I-beam without departing from the spirit of the invention.

What I claim is—

- 20 1. In a bolster, an integral web and surrounding flange and with an opening formed centrally of the web and proportioned to receive a beam, and means surrounding the central opening and adapted for connecting the bolster and beam.
- 25 2. In a bolster, a flange surrounding a central opening and defining the limits of the bolster, means adjacent the central opening for connecting the bolster to a frame structure, and means formed at the ends of the bolster for connection with a truss-rod.
- 30 3. In a bolster, a body structure, spaced plates at the ends of the body structure and defining openings upon opposite sides of the body structure positioned to receive and engage a truss-rod.
- 35 4. In a bolster, a body structure, spaced vertical plates formed at opposite ends of the structure, and extending laterally upon op-

posite sides of the structure, and with registering openings formed in the plates upon opposite sides of the body structure. 40

5. In a bolster, means formed at opposite ends of the bolster for connecting a laterally-extending truss-rod upon opposite sides of the bolster. 45

6. In a bolster, a webbed body structure provided with a surrounding flange, and having a vertical central opening extending substantially the width of the body, and reinforcing means secured to the flange and spanning the interval of the opening at the lower side. 50

7. In a bolster, a webbed body portion having a surrounding flange and with a central beam-receiving opening extending substantially the width of the web, and reinforcing means carried by the flange above and below and spanning the interval of the central opening. 55

8. In a bolster, a laterally-extending body portion, means for securing side rails upon the opposite ends of the bolster, and a gusset proportioned to be secured to the bolster and side rail and to rigidly connect the two. 60

9. In a bolster, a webbed body portion surrounded by a limiting flange, means for securing side rails to the opposite end of the bolster, and a gusset proportioned to be secured to and rigidly connect the side-rail-limiting flange. 70

In testimony whereof I affix my signature in presence of two witnesses.

FRANCIS JERDONE, JR.
